Carl Siehl
INVENTOR.

UNITED STATES PATENT OFFICE.

CARL SIEHL, OF IONIA, MICHIGAN.

BUTTON.

Application filed August 11, 1920. Serial No. 402,846.

To all whom it may concern:

Be it known that I, CARL SIEHL, a citizen of the United States, residing at Ionia, in the county of Ionia and State of Michigan, 5 have invented certain new and useful Improvements in Buttons, of which the following is a specification.

My invention relates to improvements in buttons.

10 An important object of the invention is to provide a button of simple construction, and which may be secured to fabric or the like in a positive and reliable manner.

Other objects and advantages of the invention will be apparent during the course 15 of the following description.

In the accompanying drawings forming a part of this specification, and in which like numerals are employed to designate like 20 parts throughout the same,

Figure 1 is a central vertical section through a button embodying my invention.

Figure 2 is a perspective view of the head or outer member of the button, and, 25 Figure 3 is a similar view of the retainer or inner member of the button.

In the drawings, the numeral 5 designates the head or outer member of the button, which may be formed of bone, composition, 30 metal, or any other suitable material. The outer surface 6 may be in any suitable shape or design. The outer member embodies a shank 7, having a convexed or spherically curved face 8, to contact with the fabric 9 or the like. The shank 7 terminates inwardly of the periphery of the member 5, forming a flange 10.

The numeral 11 designates an inner retainer member, having a concaved or 40 spherically curved face 12, to conform to the curvature of the face 8 for clamping

the fabric 9 therebetween. The inner or retainer member 11 carries a screw-threaded stud 13, for insertion within a screw-threaded opening 14 in the outer member 5. 45

It is thus seen that the maximum contact area is provided between the fabric and the spherically curved faces 8 and 12, thus securely clamping the button to the fabric, and relieving the pull of the fabric from 50 the stud 13, which would tend to tear it.

It is to be understood that the form of my invention herewith shown and described is to be taken as a preferred example of the same, and that various changes in the shape, 55 size, and arrangement of parts may be resorted to without departing from the spirit of my invention, or the scope of the subjoined claim.

Having thus described my invention, I 60 claim:—

A separable button, consisting of a head having a threaded bore formed centrally therein, a reduced shank formed on one side of said head, said shank having its end 65 rounded to provide a semi-spherical surface, a retainer member, a threaded stud carried by said retaining member adapted to be received in the threaded bore in said head, the surface of said retainer member adjacent said semi-spherical surface of said shank being concaved and of the same curvature as the semi-spherical surface for binding a portion of the material therebetween to which the button is attached. 70 75

In testimony whereof, I have affixed my signature in the presence of two witnesses.

CARL SIEHL.

Witnesses:

HERBERT S. V. COOPER,
JESSIE M. HUTCHINS.
